UNITED STATES PATENT OFFICE.

ARTHUR E. PAIGE, OF PHILADELPHIA, PENNSYLVANIA.

PUMP.

Application filed March 24, 1926. Serial No. 96,935.

My invention is particularly designed and adapted for use in the art of forming what are known as artificial silk threads by the extrusion of colloids, such as the thiocarbonate of cellulose known as viscose, through a spinneret orifice, into a coagulating medium such as an aqueous solution containing sulphuric or hydrochloric acid.

The conditions under which such pumping must be effected impose difficulties which are not experienced in pumping any other material. For instance, first, viscose is an unstable compound which is not only normally extremely viscous, but tends to increase in viscosity and quickly coagulates to an approximately solid consistency if heated by the pumping operation. Second, although primarily rendered of uniform consistency, viscose not only then has an abrading action upon any surface over which it is forced, but rapidly precipitates what are termed viscoids, which appear in the normal viscose as particles of not only greater viscosity, but having greater abrasive effect upon the surfaces traversed. Third, the size of the filament is determined by the rate at which the viscose is forced through the spinneret. Fourth, the desired uniformity in diameter of the filament is only attainable by continuous maintenance of a predetermined rate of discharge; any fluctuation in such rate being manifested by corresponding differences in the diameter of the filament throughout its length, rendering the latter commercially undesirable. Fifth, the volume of viscose to be delivered to such a spinneret per unit of time is so extremely small that even slight irregularities in the delivering capacity of the pump are in fact high percentages of the total volume. For instance, the largest filament for which there is a present demand is what is termed an artificial horsehair of 450 denier, used for forming millinery braids and similar fabrics, and to form such a filament a spinneret must be supplied with viscose at a uniform rate of not more than thirteen and one-half cubic centimeters per minute. Sixth, the rate of discharge of viscose through the spinneret must be susceptible of accurate adjustment and variation to produce filaments of different sizes. Heretofore, such adjustment has been effected by operating the pumps at respectively different rates of speed; necessitating changes in the gearing connec-

tions for actuating the pumps for each change in the desired effective capacity.

Various attempts were made to supply such a spinneret by means of pumps of the reciprocatory plunger type. Even when made of hardened steel with extreme accuracy, such pumps only operate properly for a brief time, as the plungers and their casings become abraded, with consequent loss of capacity and irregularity in delivery. Therefore, recently, attempts were made to use pumps of the type including a pair of intermeshed gears, which carry the viscose in the spaces between their teeth. However, even when made of hardened steel; such pumps quickly deteriorate from abrasion at the side surfaces of the gears in the pump chamber, with consequent loss of capacity and irregularity of delivery. Moreover, even slight wear upon the pistons of pumps of the first type and the gears of pumps of the second type aforesaid are manifested by weak spots in the filaments formed by the occlusion in the filament of bubbles of air which is drawn into the viscose through the leaks in the pumps.

Moreover, in order to vary the quantity of viscose delivered by such pumps, in accordance with the diameter of the filament to be extruded, it is necessary to provide means for changing the gearing by which they are operated, and considerable loss of time and labor is inevitable in effecting such changes.

Therefore, it is the object and effect of my invention to avoid the difficulties aforesaid by providing a pump of a radically different type, wherein the viscose is continually secluded from possibility of injection of air; and changes in the rate of delivery thereof may be instantly effected without any change in the pump driving mechanism. In accordance with my invention, the pumping action is effected by pulsatory changes in the volumetric capacity of a pump chamber, without sliding movement of any part thereof; such changes being effected by flexing a diaphragm which is a wall of said chamber. In the form of my invention hereinafter described, such flexure is effected by a cam on a rotary shaft which also positively operates valves controlling an inlet port and an outlet port of said chamber; so that as the capacity of said chamber is increased by outward flexure of its wall aforesaid, viscose

is sucked into said chamber and, as said wall is reflexed, a charge of viscose is forced from said chamber toward the spinneret. Moreover, the effective capacity of the pump is variable, either by varying the stroke of said diaphragm, or by manipulation of a valve.

My invention includes the various novel features of construction and arrangement hereinafter more definitely specified.

In said drawings; Fig. I is an end elevation of a pump and its connections with a viscose supply pipe and driving gearing. Fig. II is a longitudinal vertical sectional view, taken on the line II, II in Fig. I. Fig. III is a transverse vertical sectional view, taken on the line III, III in Fig. II. Fig. IV is a transverse vertical sectional view, taken on the line IV, IV in Fig. II. Fig. V is a transverse sectional view, taken on the line V, V in Fig. II. Fig. VI is a longitudinal vertical sectional view of a modified form of my invention, in connection with a viscose supply pipe and driving gearing. Fig. VII is a transverse vertical sectional view, taken on the line VII, VII in Fig. VI. Figs. VIII and IX are fragmentary sectional views of the valve casing showing respectively different forms of valves and ports.

In Figures I to V inclusive; 1 is the viscose supply main which is common to a plurality of pumps, of which but one is shown, and which is arranged to independently supply them with viscose through respective supply ports 2 which are, conveniently, drilled holes in the wall of said conduit. The pump casing 4 has an arched base 5 fitted over said conduit 1 and is arranged to be rigidly connected therewith by the clamp plate 6 which is secured by the bolts 7 and nuts 8, which bolts extend through the flanges 9 on said casing 4 and through the flanges 10 on said clamp plate 6. Said casing 4 has the inlet 11 adapted to register with said supply port 2 and maintained in liquid tight relation therewith by the annular gasket 12 which is conveniently formed of rubber interposed between said conduit 1 and said casing 4 and fitted in the seat 14 in the latter. Said inlet 11 is conveniently formed as a drilled hole extending into the pump chamber 15 in said casing 4, which has the outlet port 16 also conveniently formed as a drilled hole extending through said casing 4 to the closure seat 18 in which is detachably fitted the closure 19 which is conveniently formed of soft rubber, which is compressed upon said conduit 1, like the gasket 12, to normally close said outlet port at that end. However, said port 16 has the branch 20 extending transversely thereto and in communication with the conduit 21 leading to the spinneret 22, and arranged to be controlled by the screw needle valve 23.

Said pump chamber 15 has the flexible wall 24 conveniently formed of a circular diaphragm of thin sheet metal, for instance, spring tempered steel, which is fitted against the annular soft rubber gasket 25 in the annular seat 26 in said casing 4 in which it is secured by the retaining ring 27 which has a circumferential screw thread 28 in engagement with the corresponding thread in said casing 4. Said diaphragm 24 is arranged to be flexed by the rotary cam 30 which is a cylindrical body rigidly connected in eccentric relation with the rotary shaft 31, conveniently by the tapered pin 32. Said eccentric is preferably provided with the annular shoe 34 in coaxial relation therewith, and anti-friction rollers 35 interposed between said cam and shoe; so that the latter may remain stationary in its contact with said diaphragm 24, while said cam rotates; although said shoe is capable of rotation. Such arrangement minimizes the wear upon said diaphragm. The oscillating effect of said cam upon said diaphragm may be varied by longitudinal adjustment of the wedge 37 which is interposed between said diaphragm 24 and said shoe 34 and secured in adjusted position by the screw 38 which extends through the slot 39 in said wedge, into engagement with said casing 4.

It is to be understood that with said wedge in a given position of adjustment, the oscillatory effect of said cam 30 upon said diaphragm 24 remains constant and, of course, such wedge adjustment may be omitted and the cam be arranged to bear upon said diaphragm 24 directly or through the medium of said shoe 34.

In either case; when said diaphragm 24 is in its normal plane position, indicated in Fig. II, the volumetric capacity of said pump chamber 15 is at its maximum, but is reduced to the extent that said diaphragm is flexed inwardly by the oscillatory action of said cam. To render such oscillatory movement of the diaphragm 24 effective to intake and expel liquid with respect to said pump chamber 15; I provide said inlet port 11 and said outlet port 16, leading to and from said pump chamber 15, with respective rotary valves 41 and 42 which are conveniently formed alike, as conical frustums, and fitted to rotate in respective seats 43 and 44 in said casing 4. Said valves are respectively connected with said shaft 31, conveniently by splines 46, so as to be positively rotated by said shaft. However, said valve 41 is rigidly connected with said shaft 31, by the set screw 47, whereas, said valve 42 is free to slide axially upon said shaft 31 but is pressed into its seat by the spring 48 which encircles said shaft 31 and is detachably secured thereon by a removable abutment on said shaft 31, conveniently consisting of the pair of jam nuts 50 engaging

the screw thread on said shaft. Of course, said spring 48 also serves to resiliently press said valve 41 into its seat, by axial thrust on said shaft 31 to the right in Fig. II.

5 Said valves 41 and 42 are provided with respective ports 52 and 53 which are grooves cut sectorally in the respective circumferences thereof, as shown respectively in Figs. IV and V. Although said valves 41 and 42 10 are alike, they are set upon said shaft 31 so that when the port 52 in the valve 41 establishes communication between said supply pipe 1 and said pump chamber 15, as indicated in Fig. IV; said valve 42 closes said 15 port 16 as indicated in Fig. V, and vice versa. Said cam 30 is so set upon said shaft 31, in relation to said valves 41 and 42, that when said inlet port 11 is opened by said valve 41, and said outlet port 16 closed by 20 said valve 42, said diaphragm 24 is permitted to assume its outermost position to suck viscose into said chamber 15, and, when said inlet port 11 is closed by said valve 41 and said outlet port 16 is opened by said valve 25 42, said diaphragm 24 is flexed to eject the viscose from said chamber toward the spinneret 22.

I find it convenient to arrange the structure aforesaid so that the displacement of 30 viscose in said pump chamber 15, effected by the oscillation of said diaphragm 24, may be of constant volume, but the effective displacement of viscose from said chamber to said spinneret may be minutely and accurately adjustably varied; by providing said casing 4 with the bypass port 55 which is conveniently formed by two drilled holes extending in transverse relation in said casing 4; said bypass port being in communication 35 with said conduit 1 through the portion of said inlet port between said conduit 1 and the valve seat 43, as shown in Fig. IV and extending into said chamber 15 aside from said seat. Said bypass 55 is provided with 40 the valve 58, which is conveniently of the needle screw type; whereby the effective area of said bypass port 55 may be adjustably varied from zero to its maximum; with the effect of correspondingly varying the 45 discharge of viscose from the pump toward the spinneret.

Of course, variation in the volume of liquid delivered by the pump with a given stroke of the diaphragm 24 may be effected 55 by rotary adjustment of the valve 41 on the shaft 31; so that the inlet port is left open, more or less, during the compression stroke of said diaphragm. Therefore, the volume of liquid delivered by said pump at each 60 stroke of said diaphragm 24 may be varied either by changing the effect of the cam 30 upon said diaphragm, by adjustment of said wedge 37, or by adjustment of the inlet valve 41, or by adjustment of the bypass valve 58.

65 I find it convenient to rotate said shaft 31

by means of the pump gear wheel 60 which is detachably rigidly connected therewith by the set screw 61. As indicated in Fig. I; said pump gear wheel 60 is in mesh with the intermediate gear 63 which is mounted to rotate freely on the stud 64 carried by the rock lever arm 65 which is hung upon said shaft 31 by its hub 66 and has the arcuate slot 68 in concentric relation with said shaft 31 to receive the set screw 69 which extends 70 through said slot into engagement with said casing 4. Said arm 65 is normally rigidly secured, in the position indicated in Fig. I, with said gear 63 in mesh with the driving gear 71 on the driving shaft 72 which may 75 be provided with a series of similar gears 71 for engagement with a series of pumps constructed and arranged as above described. However, it is to be understood that by loosening said screw 69, said rock arm 65 80 may be turned from its normal position to withdraw the intermediate gear 63 from the driving gear 71 with which it is normally connected, so that any pump in the series 85 may be thus instantly rendered idle.

In the form of my invention shown in Figs. VI and VII; the pump casing 73, which is otherwise constructed and arranged like said pump casing 4, has the pump chamber 15 provided with the annular seat 74 for 90 the diaphragm 24 recessed in the outer wall thereof, and the cam 30 is arranged to flex said diaphragm by means of the yoke 76 which encircles said cam and diaphragm and is preferably provided with the renewable shoe 77 for wearing contact with said cam, and has the set screw 79 which is axially adjustable toward and away from said diaphragm and provided with the jam nut 80 by which it may be secured in adjusted 100 position. Said diaphragm is preferably provided with the cup 81 to receive the end of said screw 79, and the latter may be adjusted to vary the effect of said cam 30 upon said diaphragm 24 and thus vary the rate of discharge of viscose from said pump chamber. The pins 83 and 84 carried by the shaft 31 in Fig. VI in engagement with notches 85 and 86 in the respective rotary valves 41 and 42, may be substituted for the splines 46 as 110 means for positively rotating said valves while maintaining them in the proper relative rotary position. Both of said valves 41 and 42 may be free to slide axially upon said shaft 31, to and from engagement with said pins, but are pressed into their seats by the spring 48 which encircles said shaft 31 and is detachably secured thereon by the jam nuts 50. However, said spring may be omitted and said valves be directly and positively pressed into their seats by adjustment 115 of said nuts.

Of course, such intermediate gears 63 and their supporting levers may be omitted, and the pump gears 60 directly connected with 120

- the driving gears 71; in which case, any pump may be rendered idle by loosening the nuts 8 on the bolts 7 and slightly turning the pump casing 4 upon the supply conduit 1. 5 In either case, the individual pumps may be adjusted or repaired without interference with the operation of any other pump in the series to which said conduit 1 and driving shaft 72 are common.
- 10 All of the metal parts which come in contact with the viscose are preferably made of ferric metal. However, the valve plugs may be of softer metal than their casing, or be formed of bakelite or similar non-corrosive 15 material, so that the wear is concentrated upon them and they may be cheaply replaced.

Fig. VIII shows a form of valve and co-operative ports arranged to open and close 20 once per revolution, whereas, Fig. IX shows a form of valve and ports arranged to open and close twice per revolution. The cam 30 would have two crests to operate the diaphragm 24 in conjunction with such valves 25 as shown in Fig. IV, but said cam would have but one crest, and may be merely an eccentric cylinder, to cooperate with valves such as shown in Fig. VIII.

Therefore, I do not desire to limit myself 30 to the details of construction and arrangement herein set forth, as it is obvious that various modifications may be made therein, without departing from the essential features 35 of my invention, as defined in the appended claims.

I claim:

1. In a pump; the combination with a casing having an inlet port and means arranged to connect a conduit therewith; said 40 inlet port extending from said conduit into a pump chamber in said casing; an outlet port from said chamber extending through said casing; a flexible metallic diaphragm fitted in said casing as a wall of said pump 45 chamber; rotary valves fitted in corresponding seats in said casing, which are in coaxial relation and respectively local to said inlet port and outlet port; each of said valves having a port; a shaft extending through said 50 valves and operatively connected therewith to turn them; means connecting said valves in predetermined relative rotary position upon said shaft; means arranged to press said valves toward their seats in compensation for wear; and a cam on said shaft in co-operative relation with said diaphragm, arranged to flex said diaphragm inwardly 55 to reduce the volumetric capacity of said pump chamber when said inlet valve is closed 60 and said outlet valve opened and vice versa; means arranged to rotate said shaft; a bypass arranged to establish communication between said conduit and said pump chamber; independently of said inlet valve; and 65 means arranged to vary the effective area of

said bypass; whereby, rotation of said cam and inlet and outlet valves causes oscillatory displacement of the liquid in said pump chamber, but the effective displacement of said liquid through said outlet is variable by 70 adjustment of said bypass valve.

2. In a pump; the combination with a casing having an inlet port and means arranged to connect a conduit therewith; said inlet port extending from said conduit into 75 a pump chamber in said casing; an outlet port from said chamber extending through said casing; a flexible metallic diaphragm fitted in said casing as a wall of said pump chamber; rotary valves fitted in corresponding seats in said casing, which are in coaxial relation and respectively local to said inlet port and outlet port; each of said valves having a port; a shaft extending through said valves and operatively connected therewith to turn them; means connecting said valves in predetermined relative rotary position upon said shaft; means arranged to press said valves toward their seats in compensation for wear; and a cam on said shaft 80 in co-operating relation with said diaphragm, arranged to flex said diaphragm inwardly to reduce the volumetric capacity of said pump chamber when said inlet valve is closed and said outlet valve opened and vice 85 versa; and means arranged to rotate said shaft.

3. In a pump; the combination with a casing inclosing a pump chamber, and having a fluid inlet port and fluid outlet port; of 100 means arranged to open and close said ports in alternation, including rotary conical plug valves fitted, in axial alinement, in complementary seats in said casing respectively local to said ports; a shaft connecting said valves in predetermined relative circumferential positions; means tending to relatively axially shift said valves, to compensate for wear between the valves and their seats, including a spring encircling said shaft 105 and an abutment on said shaft for said spring; and means arranged to alternately increase and diminish the volumetric capacity of said chamber in definite relation with the operation of said valves, including a 110 wall in said chamber which is secured in substantially stationary relation with said casing at its perimeter and flexible intermediate of its area; and means arranged to flex said wall, including a cam carried by said shaft between said valves; and means arranged to rotate said shaft.

4. In a pump; the combination with a casing inclosing a pump chamber, and having a fluid inlet port and fluid outlet port; of 115 means arranged to open and close said ports in alternation, including rotary valves fitted, in axial alinement, in seats in said casing respectively local to said ports; a rotary shaft connecting said valves in predeter- 120

- mined relative circumferential positions; means tending to relatively axially shift said valves, to compensate for wear between the valves and their seats, including a spring 5 encircling said shaft; and means arranged to alternately increase and diminish the volumetric capacity of said chamber in definite relation with the operation of said valves, including a flexible wall in said 10 chamber, substantially stationary at its perimeter; and means arranged to flex said wall, including a cam carried by said shaft and means arranged to rotate said shaft.
5. In a pump; the combination with a casing 15 inclosing a pump chamber, and having a fluid inlet port and fluid outlet port; of valves arranged to open and close said ports in alternation; a rotary shaft arranged to operate said valves; and means arranged to alternately increase and diminish the volumetric capacity of said chamber in definite relation with the operation of said valves, including a flexible wall in said chamber; and means arranged to flex said wall, includ- 20 ing a cam carried by said shaft; and means arranged to rotate said shaft, including a gear on said shaft, a driving gear in spaced relation with said first gear, and an intermediate gear between said other gears; said 25 intermediate gear being adjustably movable to alternately connect and disconnect said driving gear with said pump.
6. In a pump; the combination with a casing 30 inclosing a pump chamber, and having a fluid inlet port and fluid outlet port; of valves arranged to open and close said ports in alternation; a shaft arranged to operate said valves; and means arranged to alternately increase and diminish the volumetric capacity of said chamber in definite relation with the operation of said valves, including a flexible wall in said chamber; means arranged to flex said wall, by rotation of said shaft; and means arranged to ro- 35 tate said shaft, including a gear on said shaft, an intermediate gear continually in mesh with said shaft gear, and means whereby said intermediate gear may be shifted, in its plane, to alternately engage and dis- 40 engage a driving gear.
7. In a pump; the combination with a casing 45 inclosing a pump chamber, and having a fluid inlet port and fluid outlet port; of valves arranged to open and close said ports in alternation; means arranged to positively operate said valves; and means arranged to alternately increase and diminish the volumetric capacity of said chamber in definite relation with the operation of said valves, including a flexible wall in said chamber, and means arranged to flex said wall, including a train of gearing, movable to alternately render said pump operative and inoperative.
8. In a viscose pump, the combination 50 with a pump casing having a base with a pump chamber recessed in one side thereof and a conduit at the opposite side thereof; of means securing said casing to said conduit; said casing having an inlet port ex- 55 tends from said conduit into a pump chamber in said casing and an outlet port from said chamber; a flexible diaphragm fitted as a wall of said pump chamber; means securing the margin of said dia- 60 phragm in liquid tight relation with said casing; rotary valves fitted in corresponding seats in said casing, which are in coaxial relation and respectively local to said inlet port and outlet port; a shaft extending 65 through said valve plugs and operatively connected therewith to turn them; means on said shaft arranged to press said valves toward their seats, in compensation for wear upon their conical surfaces; a cam on said shaft between said valves; a yoke between said cam and diaphragm, having means adjustable toward and away from said dia- 70 phragm, and arranged to flex said dia- 75 phragm inwardly to reduce the volumetric capacity of said pump chamber when said inlet valve is closed and said outlet valve opened, and vice versa; and means arranged to rotate said shaft; whereby rotation of said cam and inlet and outlet valves causes 80 pulsatory displacement of the liquid in said pump chamber at a rate which is constant but variable by adjustment of said yoke.
9. In a viscose pump, the combination 85 with a pump casing having a base with a pump chamber recessed in one side thereof and a conduit at the opposite side thereof; of means securing said casing to said conduit; said casing having an inlet port ex- 90 tends from said conduit into a pump chamber in said casing and an outlet port from said chamber; a flexible diaphragm fitted as a wall of said pump chamber; means securing the margin of said dia- 95 phragm in liquid tight relation with said casing; rotary valves fitted in corresponding seats in said casing, which are in coaxial relation and respectively local to said inlet port and outlet port; a shaft extending 100 through said valve plugs and operatively connected therewith to turn them; means on said shaft arranged to press said valves toward their seats, in compensation for wear upon their conical surfaces; a cam on said shaft between said valves; a yoke between said cam and diaphragm, having means ar- 105 ranged to flex said diaphragm inwardly to reduce the volumetric capacity of said pump chamber when said inlet valve is closed and said outlet valve opened, and vice versa; and means arranged to rotate said shaft; whereby rotation of said cam and inlet and outlet valves causes 110 pulsatory displacement of the liquid in said pump chamber at a rate which is constant but variable by adjustment of said yoke.
10. In a pump; the combination with a 115

casing inclosing a pump chamber and having two oppositely inclined axially alined conical valve seats and fluid inlet ports upon opposite sides of one valve seat and fluid outlet ports upon opposite sides of the other valve seat; of conical valves arranged to open and close said ports in alteration; means arranged to positively operate said valves, including a shaft common to both of them upon which said valves are relatively axially

adjustable; and means arranged to alternately increase and diminish the volumetric capacity of said chamber in definite relation with the operation of said valves, including a single flexible wall in said chamber, and 15 means arranged to flex said wall.

In testimony whereof, I have hereunto signed my name at Philadelphia, Pennsylvania, this eleventh day of March, 1926.

ARTHUR E. PAIGE.
